UNITED STATES PATENT OFFICE.

JOHN ROEDER, OF CHICAGO, ILLINOIS, ASSIGNOR TO JACOB W. LARKIN AND
ALEXANDER O'HARE.

ELECTRIC SIGNAL DEVICE.

1,256,262.

Specification of Letters Patent. Patented Feb. 12, 1918.

Application filed November 6, 1914. Serial No. 870,622.

To all whom it may concern:

Be it known that I, JOHN ROEDER, a subject of the Emperor of Germany, residing at Chicago, in the county of Cook and State 5 of Illinois, have invented certain new and useful Improvements in Electric Signal Devices, of which the following is a specification.

This invention relates to electric signal 10 devices, and more particularly an audible signal or alarm in the form of an electric bell.

The invention has for its object to provide an improved electric bell, the same embodying certain novel features of construction to 15 be hereinafter described and claimed.

A further object of the invention is to provide the bell with a visual signal in the form of an electric lamp.

20 The invention also has for its object to provide a novel and improved mounting for the bell and the lamp, whereby the parts are securely held and not liable to be jarred loose.

25 In order that the invention may be better understood, reference is had to the accompanying drawing, in which Figure 1 is a side elevation and Fig. 2 a front elevation of the apparatus, the bell being shown in section; Fig. 3 is a vertical section on the line 3—3 of Fig. 2, and Fig. 4 is a horizontal section on the line 4—4 of Fig. 2.

Referring specifically to the drawing, 5 denotes a standard which supports the bell 6, as well as the other parts of the apparatus. The upper end of the standard has a boss 7 which is provided with a threaded opening to receive a threaded tubular stem 8, said stem rising a suitable distance from 35 the boss and supporting the casing 9 of a lamp. The lamp casing has a threaded opening at its base so that it may be screwed on the stem 8. In the top of the bell 6 is an opening through which the stem 8 passes, 40 the bell being located between the base of the lamp casing 9 and the top of the boss 7, and between which parts it is securely clamped by screwing down the lamp casing until the bell is clamped against the boss.

45 A washer 10 is interposed between the bell and the boss.

The standard 5 has outstanding, spaced bracket arms 11 and 12. On the arm 11 is mounted an electro-magnet 13, the armature 55 14 of which carries the hammer 15 of the

bell 6. The armature is pivotally supported on a pin 16 carried by the standard 5, the latter having an opening 17 across which the pin extends, and in which opening the pivoted end of the armature works.

To the armature 14 is made fast a spring 18 one end of which extends in a bow from the rear end of the armature and hooks into a recess 19 in the standard 5, the other end of the spring extending along the armature, 35 in spaced relation therewith, and carrying at its extremity a contact piece 20. This contact piece is designed to engage a contact pin 21 carried by the bracket arm 12 and insulated therefrom as shown in Fig. 3. The 75 action of the spring normally holds the part 20 in contact with the pin 21, the contact being broken when the armature 14 is attracted by the magnet 13 being energized.

The standard 5 carries a terminal 22 to 75 which one of the circuit wires 23 of the magnet 13 is connected, the electric current being taken from a battery or other suitable source which has not been shown. The wire 23 is connected to the winding of the magnet and from the latter a wire 24 extends to the contact pin 21. The terminal 22 is suitably insulated from the standard 5, and the latter also carries a terminal 25 to which the other circuit wire 26 of the magnet is 80 connected. The terminal 25 is not insulated from the standard, and one side of the electric circuit is therefore grounded on the standard. The spring 18 is in electrical connection with the standard through the parts 90 16 and 14. It will therefore be evident that when the circuit is closed, the magnet 13 is energized and the armature 14 is attracted. This breaks the circuit by the separation of the contacts 20 and 21. As the magnet is 85 now de-energized it ceases to attract the armature and the latter is pulled back by the spring 18. The contact 20 now again touches the contact 21, and the circuit is again closed, whereupon the armature is 100 again attracted. The armature is thus oscillated, and as it carries the hammer 15, the bell 6 is sounded by the latter.

The lower end of the standard 5 has a threaded stem 27 for connection to a suitable support.

The casing 9 contains a socket 28 for an electric lamp 29, the latter having a base which is screwed into the socket. The lamp is an ordinary incandescent lamp. The 110

- electric current for the lamp is obtained from the magnet circuit in the following manner: The lamp base has the usual contact which engages the upper end of a wire 30 5 passing through the stem 8, said wire being insulated except at its ends. The lower end of the wire seats on a spring strip 31 carried by but insulated from the standard 5. To this strip is connected a branch conductor 32 10 leading from the terminal 22. The lamp is also grounded on the standard. Thus, when the magnet circuit is closed, the lamp is lighted. The lamp however burns steady as it is not in that part of the magnet circuit 15 which is intermittently interrupted by the contacts 20 and 21. The spring strip 31 presses against the lower end of the wire 30, whereby separation of the parts by vibration is effectually prevented.
- 20 The lamp casing 9 has a cover 33 between which and the lamp 29 is placed a spring 34, which latter holds the lamp from being jarred loose.
- 25 The apparatus hereinbefore described is designed more particularly as an alarm for automobiles and launches. If applied to the

former it may be mounted on the radiator cap.

I claim:—

A signal apparatus comprising a bell, a 30 standard, a tubular threaded stem carried by the standard and projecting from the top thereof, the bell being mounted on the projecting end of the stem, a lamp casing having a threaded opening in its base into which 35 the projecting end of the stem, above the bell, is screwed, the bell being clamped between the top of the standard and the base of the lamp casing, an electric lamp in the casing, said casing having an integral socket 40 in line with the stem to receive the lamp base, a conductor for the lamp circuit passing through the stem into the socket and projecting from the lower end of the stem, and a contact plate on which the projecting lower 45 end of the conductor bears.

In testimony whereof I affix my signature in presence of two witnesses.

JOHN ROEDER.
